UNITED STATES PATENT OFFICE.

SAMUEL KEISLING AND THOMAS N. BABB, OF MONROE, TENNESSEE.

SPINNING-MACHINE.

SPECIFICATION forming part of Letters Patent No. 224,700, dated February 17, 1880.

Application filed August 26, 1879.

To all whom it may concern:

Be it known that we, SAMUEL KEISLING and THOMAS N. BABB, of Monroe, in the county of Overton and State of Tennessee, have invented certain new and useful Improvements in Spinning-Machines; and we do hereby declare that the following is a full, clear, and exact description of the invention, which will enable others skilled in the art to which it appertains to make and use the same, reference being had to the accompanying drawings, and to letters of reference marked thereon, which form a part of this specification.

Our invention relates to an improvement in hand-spinning machines.

It consists in a new and novel arrangement for drawing out the thread and spinning and winding it, as will more fully hereinafter be set forth.

20 In the drawings, Figure 1 is a side elevation, showing the swinging arm in position when the thread is drawn out to be spun. Fig. 2 is a detail view, showing the staff with its extension-bar for adjusting my device to 25 rooms of different heights. Fig. 3 is a front elevation with the swinging arm drawn in position after winding the thread just spun and before drawing out additional thread.

A is a vertical staff or support, to which the 30 working mechanism of our device is attached. It is provided on its rear upper side with a bar, a, having a vertical slot, a', and attached by set-screws through the slot, so that it may be moved vertically in either direction and 35 set to accommodate the staff to a room of any height.

Upon the upper end of the slotted bar is a 40 hinged disk, a², with a screw loosely passing through its center, to be fastened in the ceiling or other suitable place and act as a swivel for the staff A to turn on, that it may be accommodated to any desired position. The hinge allows the staff to be raised to the ceiling, where it may be secured out of the way when not in 45 use.

At the lower end of the staff A is affixed a foot-piece extending to one side, and having an upward-projecting end so arranged as to receive and pivot a treadle, a⁴, between it and 50 the bar or staff A. The staff A is also provided on its treadle side with an arm, a⁵,

bowed downward, and having a hole or bearing in its end corresponding to one in the staff A, to receive a pin or axle.

B is a swinging arm having a large and 55 small bifurcated end, and provided each with holes or bearings through the ends of their arms to receive a pin or axle. The large end is pivoted or swung upon a pin through the bearings in the wheel-frame a⁵, and has a large 60 and small pulley joined together on the same pin or axle between its arms, and made to operate independent of it. In the other and loose end is a small pulley, b², held to its place by a long needle or pin passing through it and 65 the bearings of the arm, and acting as a combined axle and thread-spindle b⁷.

Intermediate the arm a⁵ and the treadle a⁴ is a crank-pulley, b³, pivoted to the staff A on its treadle side and made to operate so that 70 a band passing around it and the small pulley b' will turn the larger pulley b, and a band passing around it (the pulley b) and the small pulley b² causes the latter to revolve rapidly.

b⁴ is a curved pitman connecting the inner 75 end of the treadle a⁴, at b⁶, to the outside of the inner arm of the pivoted end of the bifurcated swinging arm B at b⁵, and made to operate so that pressing the foot upon the outer end of the treadle a⁴ will vertically raise 80 the pitman, which, in turn, elevates the swinging arm B to a horizontal position ready for spinning, as is shown in Fig. 1.

What we claim is—

The combination, with the spindle b⁷, provided with a pulley, b², and fixed in the free end of the arm B, and the swinging arm B, hinged on a pin or axle, b⁸, near the upper end of the staff A, of the staff A, pulleys b b', journaled on axle b⁸, crank-wheel b³, pitman 90 b⁴, with its treadle a⁴, and the necessary cords or belts for driving the pulleys, all arranged to operate substantially as and for the purposes set forth.

In testimony that we claim the foregoing as 95 our own we affix our signatures in presence of two witnesses.

SAMUEL KEISLING.
THOMAS N. BABB.
